UNITED STATES PATENT OFFICE.

MARION A. ANDREWS, OF SYRACUSE, NEW YORK, ASSIGNOR OF ONE-HALF
TO JAMES M. ANDREWS, OF SAME PLACE.

ANTI-FRICTION JOURNAL-BEARING.

SPECIFICATION forming part of Letters Patent No. 449,893, dated April 7, 1891.

Application filed May 9, 1890. Serial No. 351,155. (No model.)

To all whom it may concern:

Be it known that I, MARION A. ANDREWS, of Syracuse, in the county of Onondaga, in the State of New York, have invented new and useful Improvements in Journal-Bearings, of which the following, taken in connection with the accompanying drawings, is a full, clear, and exact description.

My invention relates to the construction of anti-friction journal-bearings for axles, shafts, or arbors, and which are designed to reduce the friction.

My object is to produce an improved journal-bearing of the anti-friction species, in which the axle is grooved near its outer end, creating a head and an inner shoulder between which a ring fits loosely over the axle and lies in the groove therein, in which anti-friction rollers support and steady the ring, traveling in a groove around the periphery of the ring, and also traveling in a groove around the inner wall of the outer casing, said rollers being mounted upon separate arbors mounted or secured in annular rings and being held apart from each other by their arbors.

My invention consists in the several novel features of construction hereinafter described, and specifically set forth in the claims annexed.

The bearing is constructed as follows, reference being had to the accompanying drawings, in which—

Figure 1 is a front elevation with the cap or cover of the casing removed. Fig. 2 is a vertical section taken on radial lines X X in Fig. 1 from the center outward both ways through the center of two of the friction-rollers. Fig. 3 is a sectional elevation on a radial line on an enlarged scale from Fig. 2. Fig. 4 is a like view, on a like scale, showing the corners of the trackway in the casing, the corners of the rollers, those of the outer trackway on the loose ring, those of the inner trackway of the ring, and those of the groove in the axle, all rounded off instead of scarfed or beveled, as in Figs. 2 and 3. Fig. 5 shows the axle grooved to receive the whole width of the loose ring, the loose ring having a plain inner wall and a grooved trackway in its outer wall, the inner corners of which are

rounded and the outer ones left sharp. Fig. 6 is a view showing the axle grooved as in Fig. 5, and showing also the loose ring grooved in its inner wall producing two side trackways bearing on the axle in the groove. Fig. 7 is a view showing the inner wall of the ring grooved as in Fig. 6 and the axle provided with two grooves to receive double trackway in the ring.

A is the casing, shown as constructed in sections, each having an inner semi-circular wall 1, between the back 3 and the cover or cap 3', and 2 is a groove cut in this wall, so that when the casing-sections are placed together the grooves coincide and form an in- 65 closed grooved trackway.

B is a ring of proper length to fit loosely between the back and the cap of the casing, having a plain inner wall 4, Fig. 5, and an endless groove or grooved trackway 5 around 70 its periphery, and the inner diameter of this ring is greater than that of the axle passing through it, so that the ring is loose upon it. The inner wall of this ring may also be grooved or cut away centrally, as at 6, so as 75 to create a trackway 7 on each edge of its inner wall. The walls of this grooved trackway in the outer face of the ring may be slanted or beveled, or the outer corners of its walls may be rounded, as in Fig. 4, or the inner corners may be rounded, as in Fig. 5. The trackway in the inner wall of the casing should always be like unto that in the loose ring. Between this ring and the casing I mount rollers or wheels 8, each upon its separate arbor 8, which arbors are mounted in separate bearings in the annular rings 9, and the peripheries of these rollers fit in the grooved trackway in the casing and in loose ring and bear frictionally against both, and 85 are held apart from contact with each other by their arbors, and together support and steady the ring, and are frictionally rotated by the rotation of the ring and travel in the trackways in the ring and casing. The 90 peripheries of these rollers should always fit their trackways, whether the trackways are beveled or scarfed off or have their corners rounded.

In Fig. 4 I show the outer corners of the 100

groove in the axle C rounded off, and the inner corners of the trackway on the inner wall of the loose ring are correspondingly rounded.

The groove or trackway in the axle creates 5 a head *h*, which bears against the outer end of the ring, and an inner shoulder *m*, which bears against the inner end thereof, and these control the end-thrust of the axle.

It will be seen that by beveling or rounding 10 the trackways in the ring and casing I give greater bearing for the rollers, and thus steady and support them better and give further protection against end-thrust, and, further, the beveled or rounded corners of the 15 trackways operate as guides for the rollers and hold them in line against the end-thrust, besides increasing their frictional bearing-surfaces to prevent slipping. The same is also true to a large extent as to the ring fitting the groove in the axle.

What I claim as my invention, and desire to secure by Letters Patent, is—

1. A sectional journal-casing having an endless grooved trackway in its inner wall scarfed 25 on its edges, a central ring having an endless grooved trackway in its periphery scarfed on its edges, and rollers fitting into both of said grooved trackways and mounted between an-

nular rings upon and held apart by separate arbors supported by the annular rings and 30 traveling in the trackways aforesaid, in combination with an axle grooved to receive the inner wall of the ring and fitting loosely through said ring.

2. A sectional journal-casing having an end- 35 less grooved trackway in its inner wall scarfed on its edges, a central ring having an endless grooved trackway in its periphery scarfed on its edges, and rollers fitting into both of said grooved trackways and mounted between an- 40 nular rings upon and held apart by separate arbors supported by the annular rings and traveling in the trackways, said ring further provided with an endless inwardly-projecting trackway upon its inner wall fitting into 45 a groove in the axle, in combination with an axle grooved to receive the trackway upon the inner wall of the ring and fitting loosely through said ring.

In witness whereof I have hereinunto set my 50 hand this 3d day of May, 1890.

MARION A. ANDREWS.

In presence of—

HOWARD P. DENISON,
F. T. DENISON.
